UNITED STATES PATENT OFFICE.

FRANZ MÄRTENS, OF ELBERFELD, GERMANY.

TAMPING-MACHINE.

1,320,258.

Specification of Letters Patent. Patented Oct. 28, 1919.

Application filed June 16, 1919. Serial No. 304,672.

To all whom it may concern:

Be it known that I, FRANZ MÄRTENS, a citizen of the German Republic, and residing at Elberfeld, Germany, have invented 5 certain Improvements in Tamping-Machines, of which the following is a specification.

The invention relates to machines for tamping or ramming earth or pebbles along 10 rail-way-tracks where the earth or filling material needs to be solidly tamped under and around the sleepers or in other locations.

The present invention comprises a truck 15 furnished with any kind of motor mounted on a frame for propelling it and moving the tampers by intermediate links. A shaft is geared for rotation to an electric or gaso- lene motor for propelling by means of bevel- 20 wheels two cranked axles, provided with a plurality of cranks or their equivalent, each of which is operatively connected with one or more bars for moving the tamping devices. The bars are joined by bolts oscil- 25 lating around a displacing center of oscil- lation. To each position of this center cor- responds another position of the bolts' de- 30 viation, in the manner that all oscillations terminate in one point and likewise the di- rection of the tampers, which may be hori- 35 zontal or slanting in different directions for use in tamping or packing ballast under and around the ties of railways in any suit- able way. The tampers can be displaced or elevated to any required height by means of hand-wheels screwing on a shaft with slots for inserting the bars of the tampers.

In the accompanying drawings, Figure 1 is a side elevation of a tamping-machine.

40 Fig. 2 is a top plan view of the same. Figs. 3 and 4 are views of the tampers. Fig. 5 illustrates the manner in which the tampers work in the different positions of the displacing center of oscillation.

45 The truck is composed of suitable side frames 1, united by end-beams 2, and having pedestals to receive the axles 3 of the bevel gears 4.

The propelling device is a motor 5 geared 50 to the crank shafts 6 and 7 in the ordinary manner. At each end of the shafts 6 and 7 and at intermediate points are cranks 8, each of which is connected by a rod 9, secured by a bolt 10 to the bars 11 of the 55 tampers. For each bar 11^a shaft 12 serves as

fulcrum; in the slots 13 of which the tamper bars 11 slide, and which is secured in the lower part of the frames 1 by adjusting-blocks 14 containing hand-wheels 15, for adjusting the shaft 12 and the tamper bars 60 11 by screwing the spindle 20. The tampers can be laid horizontally in this way.

The bolt 10 is the working-point of a lever 16, that is mounted to turn with a shaft 17 in slots 18 thereof, circular to the meet- 65 ing-point of the oscillation-ways of the bolts 10, as shown in Fig. 5.

The axles 6, 7, 12 and 17 are placed in the adjusting-blocks 19 fastened lengthwise to the frame 1. By moving the adjusting-blocks toward and from each other the tamper bars can be regulated. In Fig. 5 the ways 10-1, 10-2, 10-3 are the oscillations around the different positions of the shaft 17 and I, II, III are the corresponding 75 ways of the tampers.

In Figs. 3 and 4 the tampers 21 are joined with their bars by employing pressure-springs 22 for preventing strong shocks against the bars and in order to lengthen the 80 time of the pressure against the ties.

The tamping-machine is also qualified to remove the filling material from the ties.

What I claim as new and desire to secure by Letters Patent of the United States, is— 85

1. A machine for operating upon road beds comprising drive rods, means for actuating said drive rods, tamping levers pivotally connected to said drive rods, means for adjusting the pivotal connection between 90 the drive rods and tamping levers, and means slidably engaged by said tamping levers for adjusting the positions of the tamping levers.

2. A machine for operating upon road 95 beds comprising drive means, a tamping lever pivotally connected to said drive means, means for adjusting the pivotal connection between said drive means and tamping lever, and means slidably engaged by 100 said tamping lever for angularly adjusting said tamping lever with respect to said drive means and about the pivotal connection therebetween.

3. A machine for operating upon road 105 beds comprising a movable rod, means for driving said rod, a tamping lever pivotally connected to said rod, means slidably engaged by said tamping lever for raising and lowering said lever, and an adjustable lever 110

coupled to the pivotal connection between the movable rod and tamping lever and acting to shift the pivotal connection.

4. A machine for operating upon road beds comprising a reciprocating rod, means to reciprocate said rod, a tamping lever pivotally connected to said reciprocating rod, means coupled to the pivotal connection between said rod and tamping lever for adjusting the position of the lever with regard to the rod, means slidably engaged by said tamping lever, and an adjusting device for shifting said last-named means.

5. A machine for operating upon road beds comprising crank shafts, a motor for driving said crank shafts, rods connected with the cranks on said crank shafts, tamping levers actuated by said rods, a slotted shaft through which said tamping levers are adapted to slidably engage, means for adjusting said slotted shaft, and adjusting blocks for carrying said crank and slotted shafts.

6. A machine for operating upon road beds comprising a frame, adjusting blocks on said frame, crank shafts journalized in said adjusting blocks, a motor for rotating said crank shafts, rods connected to the cranks on said crank shafts, tamping levers

actuated by said rods, a slotted shaft 30 through which said tamping levers are arranged to slide, means for adjusting said slotted shaft, and swinging levers connected to the points at which said rods and tamping levers are joined.

7. A machine for operating upon road beds comprising a wheeled frame, adjusting blocks on said frame, crank shafts journalized on said blocks, a motor for rotating said crank shafts, rods connected to the cranks on said crank shafts, tamping levers pivotally connected to said rods, spring pressed tampers carried by said tamping levers, slotted shafts also carried by said adjusting blocks, spindles with hand wheels 45 for independently adjusting said slotted shaft on said adjusting blocks, said tamping levers operating through the slots in said slotted shafts, and swinging levers connected to the pivotal connections between 50 the rods and tamping levers.

In testimony, that I claim the foregoing as my invention, I have signed my name in presence of two subscribing witnesses.

FRANZ MÄRTENS.
